LOADING CENTRIFUGAL EXTRACTOR

Hubert Krantz and Heinrich Buysch, Aachen,
Germany, assignors to firm H. Krantz, Aachen,
Germany

Application February 17, 1931, Serial No. 516,470,
and in Germany January 27, 1931

5 Claims. (Cl. 214—17)

The loading of centrifugal extractors, such as of extractors used in laundries, takes considerable time according to the nature of the material to be dried, whereby the utilization of the extractor is essentially lessened and high expenses for wages are entailed. For shortening the time of loading, it has been proposed to make the extractor basket removable so as to allow same to be loaded outside the machine. By providing two removable baskets for one extractor, it is then possible to keep the extractor constantly running except for the times required to remove and re-insert the basket. A serious drawback of this way of loading extractors consists in that just that part of the extractor—namely the basket—which is most exposed to the centrifugal forces, does not remain permanently in the extractor. The fact that the connection between the basket and its spindle must be loosened at each loading operation is a great danger for the service. Moreover, the removable baskets are always liable to be damaged on their transport through the shop. In order to meet with these drawbacks, it has been proposed to use in addition to a main basket which remains permanently in the extractor, another basket adapted to be loaded at the washing machine or elsewhere and to be placed with the material in it into the main basket. It will, however, be clear that by the use of such an additional basket the centrifugal force to be taken up by the main basket will be increased very considerably.

Now, the present invention resides in using for the loading of extractors a portable receptacle which is filled with the material to be dried at any place outside the extractor, then carried above the extractor and thereupon emptied into the extractor basket. The emptying of the receptacle may be effected either by tilting or by opening bottom flaps or the like with which the receptacle may be provided. This method renders it possible to load the extractor within a minimum of time and to leave the basket permanently in the extractor.

In order to distribute the material as uniformly as possible on the section of the basket, it is contemplated according to the invention to divide the portable receptacle into a plurality of individual chambers.

For allowing of the invention to be more readily understood, it will now be described with reference to the accompanying drawing which shows, by way of example, a receptacle according to the invention in its position of discharge above an extractor.

The portable receptacle consists of a box *a* which is open at its top. The box is divided into two chambers *b*, the bottoms of which are formed by one common discharge flap or, as shown, by two separate flaps *c*. The receptacle is adapted to be suspended on a traveling crane or the like by means of detachable ropes, chains or other suspension means *d*. *f* is a centrifugal extractor.

In laundries, the method according to the invention is, for instance, carried out as follows. An empty receptacle *a* is placed near a washing machine, filled with the wet clothes, lifted with its charge by the traveling crane, carried by the same over an extractor *f* and emptied into the basket of the extractor, preferably in one turn, by opening the bottom flaps *c*. In this manner the loading of the extractor is performed within as short a time as possible. After the receptacle has been emptied it may immediately be carried back to the washing machine for receiving another charge of clothes.

It is to be understood that the portable receptacle may be given any suitable form different from that shown; it may for example be constructed as a tiltable receptacle.

Having thus described our invention, what we claim as new and desire to secure by Letters-Patent, is:—

1. The herein described method of loading the basket of a centrifugal extractor to distribute the material in the act of loading to avoid uneven centrifugal stress in the operation of the basket, consisting in supporting a load commensurate with the capacity of the basket above the basket for delivery into the same, with the load as supported evenly distributed with respect to the axial center of the load and delivering the load into the basket of the extractor while the axial center of the load is substantially in line with the axial center of the basket.

2. The herein described method of loading the basket of a centrifugal extractor to distribute the material in the act of loading to avoid uneven centrifugal stress in the operation of the basket, consisting in supporting a load commensurate with the capacity of the basket above the basket for mass delivery into the same, with the load as supported evenly distributed with respect to the axial center of the load and delivering the load as a mass into the basket of the extractor while the axial center of the load is substantially in line with the axial center of the basket.

3. The herein described method of loading the basket of a centrifugal extractor to distribute the material in the act of loading to avoid uneven

centrifugal stress in the operation of a basket, consisting in supporting the load commensurate with the capacity of the basket above the basket for mass delivery into the basket, with the load

5 as supported divided into even, regular masses with respect to the axial center of the load and delivering the load as a mass into the basket of the extractor while the axial center of the load is substantially in line with the axial center of the
10 basket.

4. In combination with a centrifugal extractor including a rotating basket, a loading element commensurate in size with the size of the basket and designed to be selectively positioned above the basket, with the load evenly distributed about
15 the basket, with the load evenly distributed about its axial center and with this axial center in substantial alignment with the axial center of the
20 basket.

basket, and means carried by the loading element and controllable at will for delivering the load therein into the basket.

5. In combination with a centrifugal extractor including a rotating basket, a loading element commensurate in size with the size of the basket and designed to be selectively positioned above the basket, with its axial center in substantial alignment with the axial center of the basket, means in the loading element to divide the load therein into substantially equal masses beyond and with relation to the axial center of the loading element, and means carried by the loading element and controllable at will for delivering the load therein as a mass into the basket. 90
